UNITED STATES PATENT OFFICE

ZEHNDER H. CONFAIR, OF BERWICK, PENNSYLVANIA, ASSIGNOR TO CONFairs PURE FRUITS, INC., OF BERWICK, PENNSYLVANIA, A CORPORATION OF PENNSYLVANIA

DESIGN FOR A BOTTLE

Application filed March 16, 1932. Serial No. 43,207. Term of patent 7 years.

To all whom it may concern:

Be it known that I, ZEHNDER H. CONFAIR, a citizen of the United States, residing at 200 Martz St., city of Berwick, in the county of Columbia and State of Pennsylvania, have invented a new, original, and ornamental Design for Bottles, of which the following is a specification, reference being had to the accompanying drawings, forming part thereof.

Figure 1 is a development of the ornamentation on a fragmentary portion of a bottle, showing my new design, said bottle being circular in cross section. Figure 2 is a side view in elevation thereof.

I claim:

The ornamental design for a bottle, as shown and described.

ZEHNDER H. CONFAIR.
